UNITED STATES PATENT OFFICE.

JOHN WESLEY HUGHES, OF OSKALOOSA, IOWA.

CAR-COUPING.

SPECIFICATION forming part of Letters Patent No. 317,363, dated May 5, 1885.

Application filed March 19, 1885. (No model.)

To all whom it may concern:

Be it known that I, JOHN W. HUGHES, a citizen of the United States, residing at Oskaloosa, in the county of Mahaska and State of Iowa, have invented a new and useful Improvement in Car-Couplings, of which the following is a specification, reference being had to the accompanying drawings.

My invention relates to car-couplings; and 10 it has for its object to provide improved means for guiding the link to the chamber of the draw-head, and to support the pin in a raised position in such manner that it will be lowered when the cars come together.

15 A further object of the invention is to provide a car-coupling which shall be positive and effective in its operation, and one that will be strong and durable.

With these ends in view the invention consists in the improved construction and detailed 20 arrangement of parts, hereinafter fully described, and pointed out in the claims.

In the drawings, Figure 1 is a perspective view of a car-coupling constructed in accordance with my invention. Fig. 2 is a longitudinal vertical section of the same. Fig. 3 is a bottom view.

In the accompanying drawings, in which like letters of reference indicate corresponding 30 parts in all the figures, A represents the draw-bars, which are designed to be rigidly secured to the under side of the car. The said draw-bars A are arranged a sufficient distance apart to admit of a draw-head, B, sliding therein. 35 The rear ends of the draw-bars A are connected by a block, a, having a hole or opening, and secured to the rear end of the draw-head and extending through the opening in the said block a is a head-bar, b, on which is a spring, 40 c, bearing against the rear end of the draw-head at one end, and against the inner side of the block a at its other end, whereby the front end of the draw-head is normally held in a position beyond the front end of the car. The 45 draw-head is held against downward movement near its front end by a metal strap, e, which connects the draw-bars A at their forward ends.

Upon the under side of the draw-head B is 50 secured a plate, C, having its rear end turned downwardly to form a bracket, b', and provided with a hole or opening. At the forward

end of this plate C is hinged a link-guide, D, the forward end of which extends outwardly beyond the draw-head, and is provided with 55 a front face which inclines upwardly from its lower end to the lower end of the mouth of the draw-head.

E represents the pin-support, which consists of two upwardly-extending arms, E', located 60 on opposite sides of the draw-head, and having rearwardly-extending extensions e' at their upper end. These arms E extend outwardly, then forwardly, and then upwardly from opposite sides of a plate, F, located on the under 65 side of the draw-head B, said plate being held in place upon the plate C by flanges G, formed integral with the plate C, and turned inwardly to form guides. The rear end of the plate F is reduced, thus forming a shoulder, f, upon 70 which is a spring, g, bearing against said shoulder at one end, and against the bracket b' at its other end, the extremity of said plate working in the hole or opening in the bracket b'. 75

Formed integral with or secured to the arms E are outwardly-extending arms H, having their ends turned inwardly, as shown at h, and secured to the under side of the link-guide D is a plate, I, having its ends turned upwardly, 80 as shown at i, and formed with holes or openings.

Connecting the plate I and the short arms H are links J, the ends of which are turned to form hooks, which fit the holes or openings in 85 the said short arms and in the upturned ends of the plate I. Upon the front of the car are levers J', the inner ends of which are pivotally connected by a bolt, j, carrying a hook, k, which is adapted to fit a hole or opening, l, in a coupling pin, m, and said coupling-pin is adapted 90 to engage holes or openings n in the draw-head. The said levers J' are pivoted to the front of the car by means of pivoted links o.

Upon the upper side of the draw-head are 95 arranged looped guides K, which inclose the inner ends of the pivoted levers and limit the upward movement of the same, thus preventing the coupling-pin from becoming detached.

Having fully described my invention, what I claim as new, and desire to secure by Letters Patent, is—

1. In a car-coupling, the combination, with a draw-head, of pivoted levers carrying a piv-

oted coupling-pin, guides K upon the upper side of the draw-head, a longitudinally-sliding plate carrying a hinged link-guide, arms extending upwardly from said plate, and having rearwardly-extending short arms for supporting the link in a raised position, as set forth.

2. In a car-coupling, the combination, with a draw-head, of a spring-actuated plate located on the under side thereof, a hinged link-guide at the forward end of said plate, pivoted levers carrying a pivoted pin, arms for supporting the same, arms H, having inturned ends, and links J, connecting the spring-actuated plate, and the link-guide, as set forth.

3. In a car-coupling, the combination, with a longitudinally-sliding draw-head, and a

spring arranged upon the rear end of the same, of pivoted levers carrying a pivoted coupling-pin, a longitudinally-sliding spring-actuated plate having upwardly-extending arms provided with rearwardly-extending extensions, and arms having their outer ends turned inwardly, and a hinged link-guide pivotally connected with said outwardly-extending short arms, as set forth. 20

In testimony that I claim the foregoing as my own I have hereto affixed my signature in presence of two witnesses. 25

JOHN WESLEY HUGHES.
